UNITED STATES PATENT OFFICE.

CHARLES P. ANDERSON, OF SEATTLE, WASHINGTON.

COMBINED MEASURING AND LOCKING DEVICE FOR VALVES.

1,169,906.

Specification of Letters Patent.

Patented Feb. 1, 1916.

Application filed March 10, 1914. Serial No. 823,667.

To all whom it may concern:

Be it known that I, CHARLES P. ANDERSON, a citizen of the United States, residing at Seattle, in the county of King and State of Washington, have invented certain new and useful Improvements in Combined Measuring and Locking Devices for Valves, of which the following is a specification.

This invention relates to valves such as are employed for dispensing liquids and has particular reference to the valves of irrigating systems.

The object of the present invention is the provision of conveniently operated and reliable means whereby a valve may be regulated to afford passage for a selected flow of liquid and also to provide means for securing the valve in such predetermined positions.

With these ends in view, the invention consists in the novel construction and adaptation of devices, as will be hereinafter described with reference to the accompanying drawings, wherein—

Figure 1 is a view in vertical section of a valve with my invention applied thereto. Fig. 2 is a plan view of the same with the lock omitted. Fig. 3 is a perspective view of the gage member.

The valve body 1, as illustrated, is formed with an exteriorly threaded outlet 2 and an inlet provided with internal threads to receive the coupling 3 having internal threads for engaging with a supply pipe. The end 4 of the coupling 3 which extends into said body is machined to serve as a seat for the valve proper; in practice said coupling is made of brass or other metals which will withstand the corrosive action due to alkali or other chemicals carried in water.

The valve 5, in the illustrated example, is of the disk-type and has secured to its underside a disk 5¹ of leather or other suitable yielding material to make a tight closure with the referred to seat.

6 represents the valve spindle extending through the bonnet-member 7 of the body and having the usual hand-wheel 8 riveted or otherwise rigidly secured to its upper end.

The bonnet is interiorly screw-threaded at 9 to receive the threaded portion 10 of the valve-spindle and 11 is a stuffing box provided upon said bonnet.

All of the aforesaid parts of the valve are or may be of the usual or suitable construction.

According to the present invention, the bonnet 7 is formed with or has secured thereto a bracket-element 12 through which extends an opening 13 to serve as a guide for 60 the stem 14 of a T-shaped measuring device having at its top oppositely directed branches or arms 15 and 16. The branch 15 is provided with a hole 17 to receive the valve-spindle 6 and the other arm 16 is provided 65 with a hole 18 to receive the bow 19 of a padlock 20 when the same engages the hand-wheel 8, as shown in Fig. 1. The branch 15 of said measuring device is held against the wheel-hub 8¹ by any suitable means such 70 as a shoulder provided on the spindle or, as shown, by means of a pin 21 inserted in a hole provided in the spindle below the branch 15. Said stem is provided with graduated marks 22 which are arranged to register with the top surface of the guide or bracket 13 to indicate the amount of the 75 valve opening.

The device may be adjusted to compensate 80 for wear and with respect to the scale markings by regulating the position of the seat 4 relatively to the valve by screwing the coupling 3, as may be required, into or out of the socket provided therefor in the valve body.

The measuring device is connected with 85 the spindle to travel with the valve, when the latter is moved through the instrumentality of the hand-wheel, and may be secured in selected positions by means of the 90 padlock, as before explained. The graduated scale registers zero when the valve is closed, and as the valve is withdrawn from its seat, the scale registers the amount of 95 opening or the effective area of the passage 95 for the flow of water or other liquid. By means of the measuring device, the flow may be readily determined thus:—for example, assuming that the scale of the measuring device indicates that the valve is 100 raised to afford an opening having an area of three inches at which it remains for twelve hours with a substantially constant head, then with these elements known—that is, time, pressure and area—the quantity of water passing the valve can be calculated.

The advantages of the invention reside, principally, in the facility with which the 105 amount of water delivered through the valve may be determined and also in the provision of improved means whereby the valve may

be locked in adjusted position by an ordinary padlock.

Having described my invention, what I claim is—

- 5 1. The combination with a valve provided with a spindle and a hand wheel, of a measuring device connected with said spindle to move axially therewith and indicate the extent the valve is opened and a perforated
- 10 10 arm provided on said measuring device to engage a lock whereby said measuring device may be locked to said handwheel to prevent rotation thereof.
- 15 2. In apparatus of the class described, a valve-spindle, a hand-wheel therefor, a T-shaped device having a stem and two branches, one of said branches being connected with the valve-spindle and the other branch being adapted to be connected by
- 20 20 means of a padlock to said hand-wheel to prevent the latter being rotated.
- 25 3. In apparatus of the class described having a rotary valve-spindle and a hand-wheel secured to said spindle for operating the valve, of a device connected with the spindle to travel therewith in an axial direction only, and means engageable with both the device and the hand-wheel to secure the spindle against rotation.
- 30 4. In apparatus of the class described, the

combination with the body having a bonnet provided with a bracket-element, a valve, a rotary spindle therefor and a hand-wheel for rotating the spindle to actuate the valve, of a device engaging said bracket-element and connected with the valve to travel in unison therewith, and means for securing the device to the hand-wheel to prevent the rotation of the latter.

5. The combination with a valve provided with a spindle and a hand-wheel therefor, of a measuring device connected with said spindle to have movement axially therewith and provided with an apertured branch element to afford means engaging a padlock whereby said device may be coupled to said wheel to prevent the rotation of the latter, and a guide connected with the valve-body for maintaining the measuring device in upright position, said measuring device being provided with graduated marks arranged to progressively register with said guide to indicate the extent the valve is opened.

Signed at Seattle, Wash., this 28th day of February, 1914.

CHARLES P. ANDERSON.
